SPINDLE

Frederic E. Banfield, Jr., Saco, Maine, assignor,
by mesne assignments, to Saco-Lowell Shops,
Biddeford, Maine, a corporation of Maine

Application March 21, 1935, Serial No. 12,120

2 Claims. (Cl. 308—151)

This invention relates to spindles of the type used in spinning and twister frames. It is more especially concerned with the mounting of the spindle in the base and bolster of a spindle structure.

In connection with the twisting of very fine yarn and thread, it is necessary to have the traverse of the ring rail correspond with a high degree of accuracy to the distance between the heads of the spools or bobbins. The present invention aims to devise means for so positioning the spindles vertically that this result can be conveniently attained.

The nature of the invention will be readily understood from the following description when read in connection with the accompanying drawing, and the novel features will be particularly pointed out in the appended claims.

In the drawing,

Figure 1 is a vertical, sectional view of a spindle structure embodying features of this invention;

Fig. 2 is a side elevation on a larger scale of the spindle bolster;

Fig. 3 is a plan view of the bolster;

Fig. 4 is a perspective view of the device for locking the bearing step in its adjusted position;

Fig. 5 is a bottom view of the step; and

Fig. 6 is a sectional view of the step and its associated parts on a larger scale.

The construction shown in the drawing comprises a base 2 of a common form equipped with the usual tubular extensions 3 and 4 projecting, respectively, above and below the main body of the base. Mounted in the base is a bolster 5

35 provided near its upper end with a shoulder 6 to rest on the upper end of the extension 3 of the base, and thus to support the bolster in a fixed position in the base. A spindle blade 7 is mounted in the bolster and carries the usual whirl 8, the lower end of the spindle being supported in a bearing step 10.

For the purpose of positioning the spindle accurately in the desired vertical relationship to the traverse of the ring rail, or other parts associated with the spindle structure, the step 10 is externally screw threaded and the lower end of the bolster 4 is internally threaded to receive the threaded portion of the step. Also, the lower end of the step is given the form of a disk-like head 12 which is notched at intervals, as best shown in Fig. 5, for engagement with the vertical blade 13 of a retaining device or keeper. This device is made of spring steel, or other resilient material, and it includes a C-shaped upper 55 end portion adapted to embrace a portion of the

bolster, both the parts 13 and 14 fitting into grooves provided to receive them in the lower portion of the bolster so that these members are located entirely within the lateral dimensions of the bolster.

It will be evident from an inspection of Figs. 1 and 6, that with this construction the vertical position of the spindle blade can be adjusted by threading the step 10 in or out of the lower end of the bolster. Also, that the keeper 13 holds the step securely in its adjusted position and prevents any accidental displacement of it. Due to the screw threaded connection between the bolster and the step, the adjustment may be made with a high degree of accuracy. It should also be observed that this adjusting movement does not disturb the relationship between the bolster and the base, this relationship remaining constant, due to the fact that the shoulder 6 of the bolster rests on the upper end of the base. Nor does this adjustment disturb the normal running relationship between the spindle and the bolster since the bearing provided in the upper portion of the bolster is straight or of cylindrical form, and the spindle is of the same shape so that the adjustment merely moves the spindle up or down in this bearing. The parts required in effecting this adjustment add relatively little to the expense of manufacture of the structure, and they provide a convenient means for producing the accurate vertical relationship between the spindle and the traverse of the ring rail which is highly desirable for some purposes, such for example, as those above mentioned.

Having thus described my invention, what I desire to claim as new is:

1. In a spindle structure, the combination of a spindle base, a bolster suspended in a fixed position in said base and having lateral bearings in the base at both upper and lower portions thereof serving to hold it in a stationary relationship to the base during operation, said base including a part to rest on the spindle rail and also a tubular imperforate extension projecting below said part and forming an oil well, a spindle blade mounted in said bolster, a bearing step for the lower end of said blade screw threaded into the lower end of the bolster for vertical adjustment relatively to both the bolster and said base to vary the vertical position of said blade relatively to the base, the step being supported above the bottom of said well, the upper portion of said bolster being provided with a cylindrical bearing for said blade in which the spindle is moved

by said adjustment of the step while maintaining undisturbed the running relationship between the blade and said cylindrical bearing, and connections between said bolster and said step for holding the step in its various positions of adjustment.

2. In a spindle structure, the combination of a spindle base, a bolster suspended in a fixed position in said base and having lateral bearings 10 in the base at both upper and lower portions thereof serving to hold it in a stationary relationship to the base during operation, said base including a part to rest on the spindle rail and also a tubular imperforate extension projecting 15 below said part and forming an oil well, a spindle blade mounted in said bolster, a bearing step for the lower end of said blade screw threaded

into the lower end of the bolster for vertical adjustment relatively to both the bolster and said base to vary the vertical position of said blade relatively to the base, the step being supported above the bottom of said well and provided with peripheral notches at its lower portion, the upper portion of said bolster being provided with a cylindrical bearing for said blade in which the spindle is moved by said adjustment of the step while maintaining undisturbed the running relationship between the blade and said cylindrical bearing, the lower part of the bolster having a circumferential groove therein, and means fitting in said circumferential groove and said notches for holding the step in its various positions of adjustment.
